UNITED STATES PATENT OFFICE.

MICHAEL H. REAP, OF SCRANTON, PENNSYLVANIA.

COAL-HANDLING-JIG GATE.

1,252,947.

Specification of Letters Patent. Patented Jan. 8, 1918.

Application filed May 10, 1917. Serial No. 167,636.

To all whom it may concern:

Be it known that I, MICHAEL H. REAP, a citizen of the United States, and a resident of Scranton, in the county of Lackawanna and State of Pennsylvania, have invented a new and Improved Coal-Handling-Jig Gate, of which the following is a full, clear, and exact description.

Among the principal objects which the present invention has in view are: to provide means for separating coal from base mineral associated therewith; to avoid waste of the coal; to facilitate the operation of the mechanism for separating said materials; and to avoid the unintentional increment of weight on operating parts of the separating mechanism.

Drawings.

Figure 1 is a longitudinal vertical section of a coal-handling jig equipped with a gate constructed in accordance with the present invention;

Fig. 2 is a vertical section on an enlarged scale, the section being taken as on the line 2-2 in Fig. 1;

Fig. 3 is a cross section on an enlarged scale, of the gate and housing therefor.

Description.

Heretofore jigs of the character mentioned have employed gates or obstructions to prevent the delivery thereunder of the base minerals associated with the coal as mined and delivered therewith to the jig. One form of the previous construction is disclosed in United States Patent No. 1,217,826, granted to me February 27, 1917, for regulator for separators. In the construction disclosed by the mentioned patent, two causes exist which operate detrimentally to the perfect functioning of the jig. These objections may be broadly stated as the cramping of the gate and the float regulating the same with the consequent imperfect operation of said gate and float. To overcome this objection, the present invention embodies a housing in which a gate 8 is vertically reciprocated.

The housing is bolted rigidly to a cross beam or header 9. Above the header 9, a metal sill 10 opens to a chute 11 wherein travels a conveyer 12, which is provided at intervals with blades 13 for engaging the

coal A delivered to the conveyer 12 up the said conveyer to the delivery end thereof. 55

Below the header 9, an opening or gateway 14 gives access to a second chute 15, wherein a belt conveyer 16 operates. The belt conveyer 16 has a series of blades 17, which engage the base mineral, such as rock B, which has been separated from the coal in the breaker and by the operation of the water C in the jig.

As seen best in Fig. 2 of the drawings, the gateway 14 is partially closed by the gate 8. The lower edge of the gate 8 has a series of teeth 20 to facilitate the operation of sinking the said gate downward through the mass of base mineral B in front of the gateway 14. Normally the body of the gate 8 is contained within the housing formed by plates 21 and 22. The plates 21 and 22 are held as shown best in Fig. 3 of the drawings, by bolts 19. The bottom opening of the housing or that between the plates 21 and 22 is such as to neatly fit the gate 8 to form a guide therefor. A further guide for the said gate is provided by the boss 23 through bores formed in which extend suspension rods 24. The rods 24, as seen best in Fig. 2 of the drawings, are pivotally connected with the levers 25 of the gate suspension mechanism.

As seen best in Fig. 3 of the drawings, an inclined perforated bench 26 is mounted on the plate 22. The bench 26 is extended from the gate 8 to substantially the level of the upper part of the gateway 14, thereby preventing the accumulation of solid material in this location. By means of the perforations 18, the bench 26 is kept clear of refuse and the coal A thereon is prevented from clogging or packing on the said bench. 90

As in most jigs of the character mentioned, the materials, such as the coal A and mineral B, are agitated by being floated partially or entirely within the container 27. The means employed for floating the said materials is water admitted to the container 27 and agitated by a plunger 28, which by means of suitable mechanism is reciprocated in a piston compartment 29. The compartment 29 is separated from the container 27 by a solid partition 30, and by a perforated bottom 31. The perforations 105 in the bottom 31 and in the bench 26 permit

the water in the tank 32 and container 27 to drive upward through the said bottom and bench to lift the material resting thereon, and to influence the body of water in 5 the container 27 to lift momentarily the coal A and mineral B, to permit the difference in specific gravity in the two materials to effect a separation thereof, the mineral B sinking faster because of its greater weight 10 than the coal A.

The degree to which the gate 8 closes the gateway 14, is determined by a float 33. The float 33, as seen best in Fig. 1 of the drawings, is cylindrical in form to above 15 the normal water level in the container 27. To avoid possibility of lodgment of coal on the float 33, the cylindrical portion is capped by a tapered top 34. Extending through the float 33 is an open-ended tube 35 provided to receive a guide rod 36. The rod 36 is rigidly mounted on the bottom 31. The tube 35 is operatively connected with the lever 25. The connection between the lever 25 and the tube 35 employs a bifurcated end of the tube which forms an elongated slot 37 through which a cross bar 38 extends, said bar being connected at the end of each of the levers 25. The upper end of 20 the slot 37 is closed and in this manner a certain amount of free or lost motion is permitted the float 33 independent of any operative effect which the said float may have on the levers 25. This independent movement of the float permits the same to operate 25 in response to the pulsation of the water in the container 27 without correspondingly operating the gate 8.

As above stated, the levers 25 are pivotally connected to suspension rods 24. The 40 levers 25 are pivotally mounted by pins 39 on the standing frame. The extensions 40 are rigidly connected with the levers 25, and have slidably mounted thereon counter-balancing weights 41. The weights 41 are 45 provided to counterbalance the floats 33 to give to the said floats any desired buoyancy. It is obvious that by moving the weights 41 toward and away from the pivot pins 39, the weight of the gate 8 and the float 50 33 is counterbalanced in part or in whole.

Operation.

When constructed and arranged as above described and as shown in the accompanying drawings, the jig operates as follows: Coal and base mineral are delivered from the breaker to the hopper 42. From the hopper 42 the mixed materials pass under the adjustable partition 43 to the tank container 27. The bottom 31 is inclined to slightly accelerate the movement of the materials from the hopper 42 to the container 27. The tank 32 is filled with water or other suitable fluid to an ascertained level,

as seen best in Fig. 1 of the drawings. The 65 water also fills the sluiceway 29.

During the operation of the jig, the plunger 28 is continuously reciprocated to cause the water in the tank 32 to surge and flow upward and downward through the 70 perforation in the bottom 31, and within the container 27 the lifting force of the water operates more efficiently on the lighter material, which in the present instance, is the coal. The coal is thus parted 75 from the base mineral. A further separation is effected due to the quicker precipitation of the base mineral when the same falls at the arrestation of the surging effect of the water. Repeated actions result in effectively separating the two materials. 80

Consequently, as the container 27 is filled, two distinct layers or strata are to be found in the contents of said container. The heavier base mineral rests on the bottom 31 85 and is carried by the incline thereof to the gateway 14, through which it flows to be 90 operated upon by the conveyer 16.

In arranging the float 33, weight is applied thereto until the specific gravity 90 thereof is intermediate that of the coal and base mineral. The immediate result of this arrangement is that the float is supported by the stratum of base mineral, sinking 95 through the stratum of coal until it rests upon the base mineral. In this manner the float operates as a gage for the quantity of base mineral deposit in the container 27.

The gate 8 is so disposed in its relation to the float 33, that when the stratum of base mineral is negligible or thin, the said gate is lowered to close the gateway 14. This disposition of the gate 8 retards the delivery of the base mineral B, causing the same to accumulate in the container 27. In the perfect operation of the jig, the stratum of base mineral B should always reach above the lower edge of the bench 26. In the normal operation of the jig, when the stratum of base mineral B approaches the level of the lower edge of the bench 26, the gate 8 is depressed sufficiently to increase the deposit of base mineral in the container 27. This insures against the possible waste of the coal A which would result should the same 110 pass below the said bench 26.

As the deposit of materials accumulates in the container 27, the upper level of the coal A rises above the sill 10 and flows thereover into the boot or receiving end of the chute 11. The operation of the conveyer 12 thereafter delivers the coal separated from the base mineral to the destination intended for said coal. Should the depletion of the coal for any reason become excessive and the increment of the base mineral be such as to be in danger of overflowing from the container 27 to the chute 11, the float 33 is lifted 125

and the gate 8 widely opened so that a quantity of the mineral B passes through the gate equal to that entering the container 27 under the partition 43. This effectively prevents the increase of the base mineral in the container 27.

It is obvious that should the base mineral be delivered to the chute 11 and thence to the coil deposit, the coal deposit would be 10 partially or entirely destroyed.

It is also obvious that in the operation, the rod 37 efficiently guides the float 38 in its rise and fall. It is equally obvious that the lift and depression of the gate 8 is not retarded by surface friction or pressure of 15 the minerals in the container 27 against the surface thereof. For these two reasons, the functioning of the gate and float is purely responsive to the accumulation of the minerals delivered to the container 27.

It is further obvious that the inclined bench 26 serves most efficiently to prevent the accession of coal to the gateway through which is normally delivered the base mineral. Also it will be seen that by arranging 25 the structure of the said bench so that the upward surging water lifts the material from the surface thereof, the tendency to accumulate or frictionally retard the flow of 30 coal over the said bench is eliminated.

Claims.

1. The combination of a jig having a container wherein coal and base mineral are 35 partially floated for stratifying the same, said jig having outlets vertically separated for independent delivery of said coal and mineral; a gate for regulating the degree of opening of the lower outlet; a float supported by said mineral at approximately the line of separation of said coal; means operatively connecting said float and said gate for disposing said gate in correspondence with said float; a housing for said gate 40 adapted for preventing the pressure of coal on said gate; a stationary fender extending into said jig from said housing to below the normal line of separation of said coal and said mineral for maintaining a fixed 45 passage for said mineral to said gate and the delivery opening controlled thereby; and

means for forcing pulsating jets of water through the region below said fender in proximity to the gate and through said fender for reducing the binding effect of 55 accumulated slate on said gate.

2. The combination of a jig having a container wherein coal and base mineral are partially floated for stratifying the same, said jig having outlets vertically separated 60 for independent delivery of said coal and mineral; a gate for regulating the degree of opening of the lower outlet; a float supported by said mineral at approximately the line of separation of said coal; means operatively connecting said float and said gate for disposing said gate in correspondence with said float; a housing for said gate 65 adapted for preventing the pressure of coal on said gate; a stationary bench extended from said housing toward the center of said 70 jig for forming a passageway in advance of said gate; and means for forcing pulsating jets of water through the region below said bench in proximity to the gate and through 75 said bench for reducing the binding effect of accumulated slate on said gate.

3. The combination of a jig having a container wherein coal and base mineral are partially floated for stratifying the same, 80 said jig having outlets vertically separated for independent delivery of said coal and mineral; a gate for regulating the degree of opening of the lower outlet; a float supported by said mineral at approximately the line of separation of said coal; means operatively connecting said float and said gate for disposing said gate in correspondence with said float; a housing for said gate 85 adapted for preventing the pressure of coal on said gate; a stationary bench extended from said housing toward the center of said 90 jig for forming a passageway in advance of said jig; and means for forcing pulsating jets of water through the region below said 95 bench in proximity to the gate and through said bench for reducing the binding effect of accumulated slate on said gate, said means embodying passages for liquid formed in said bench for permitting the liquid to surge 100 upward through said openings.
